CARPENTER'S GARMENT

Victor Thomas Powell, Sacramento, Calif.

Application June 26, 1935, Serial No. 28,564

2 Claims. (Cl. 2—51)

This invention relates to carpenters' garments and has for an object to provide a garment of this type which will dispense with braces, strings or straps for suspending the garment from the shoulders of the wearer.

A further object is to provide a sleeveless garment in which the weight of the tools and supply of nails is equalized on the shoulders and across the back to promote safety when walking in high places and to promote freedom of movement of the wearer's limbs when walking or climbing ladders and scaffolds.

A further object is to provide a flap having a set of nail pockets, and extending across the front of the garment near the lower edge thereof, the flap being fastened at one end to the garment and being removably secured by buttons or otherwise at the opposite end to the garment so that the flap may fold back and give free access to the buttons or other fasteners on the front of the garment.

A further object is to provide a garment having all the fasteners in the front to promote safety when working over water for example, when in case of a fall the garment can be torn open and discarded at once with all excess weight of tools, nails, etc., thus making it possible to swim.

A further object is to provide a garment having elongated arm holes and openings in the back and in the front reenforced with eyelets to provide for ventilation, there being also additional openings in the back of the garment which are elongated longitudinally of the garment and permit of the imperforate portions of the garment between the openings equalizing the weight of the ax, pliers, tape, and hammer upon the back of the neck.

A further object is to provide a garment having a pad on the inside just below the neck line to relieve pressure on the neck of the wearer.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification,

Figure 1 is a perspective view of the front of the garment constructed in accordance with my invention in applied position.

Figure 2 is a perspective view of the back of the garment shown in Figure 1.

Figure 3 is a detail longitudinal sectional view taken on the line 3—3 of Figure 2.

Referring now to the drawing in which like characters of reference designate similar parts in the various views, the garment 10 is in the form a sleeveless jacket or vest open at the front and overlapped, to take fasteners such as buttons 11 although clamps, zippers, hooks and eyes, or other fasteners may equally well be used. The garment is sufficient in length to cover the hips, chest and back of the wearer and is provided with elongated arm holes 12 which promote ventilation. It will be noted that the arms and legs of the wearer are unobstructed so that freedom of movement is promoted under all conditions of service such as walking and climbing ladders or scaffolds.

Ventilating openings 13 are formed in the front of the garment in the area over the shoulders and abdomen and these openings are reenforced with eyelets 14. Similar ventilating openings 15 are formed in the back of the garment below the neck line 16 and are reenforced with eyelets 17. Below the openings 15 a pair of elongated ventilating openings 18 are formed in the back of the garment in the area covering the shoulders of the wearer and below these openings are openings 19 which align with the openings 18 and have pointed lower ends 20. The lower openings are located in the area of the back of the garment covering the small of the back of the wearer. The imperforate portions 21 and 22 in the back of the garment, lying respectively outside of the openings 18 and 19 and between the openings 18 and 19 perform the function of distributing and equalizing the weight of tool pockets 23, 24 and 25 as well as strap loops 26, located below the openings, over the shoulders of the wearer when these pockets and loops are loaded with tools such as an ax, pliers, tape and hammer. The openings themselves promote adequate ventilation of the garment.

By now referring to Figure 1 it will be seen that a flap 27 extends across the abdominal portion of the garment and on one side of the line of fasteners 11 is rigidly secured to the garment by a plurality of lines of stitching 28 passing along the upper edge of the flap and along one end edge of the flap. The opposite end of the flap is secured to the garment on the opposite side of the line of fasteners 11 by means of fasteners such as buttons 29 arranged along the top edge of the flap.

- flap, and for additional security the flap is provided with tabs 30 and 31 projecting respectively upwardly from the top edge and laterally from the lower end of the end edge of the flap and secured in place by buttons 32 and 33. The front of the flap is provided with a plurality of pockets 34 to 39 inclusive to receive various sizes of nails. When these pockets are loaded the weight of the pockets is distributed uniformly over the shoulders of the wearer and upon the back of the wearer so that safety when walking in high places will be greatly promoted since the wearer may retain good balance, which is highly essential.
- 15 By unfastening the tabs 30 and 31 and disengaging the free end of the flap from the buttons 29, the flap may be folded back upon itself and the upper tab 30 may be fastened to a button 40 secured to the garment above the fastening line 20 of stitches 28 to hold the flap in position to expose the line of fasteners 11 to permit the garment being buttoned up or unbuttoned as the case may be and also to permit the garment to be ripped off at the front in case of emergency 25 such as for instance the wearer falling while working over water, so that the garment and excess weight of tools may be discarded. The button or equivalent fastener 40 by holding the flap folded prevents the nails falling out when the wearer is putting on or taking off the garment.
- It will be pointed out that below the lines of stitching 28 the flap is not secured to the garment except by means of a tab 41 and button 42 which latter holds the flap securely in position at 35 all times while at the same time the tab 31 at the opposite end of the flap may be hooked over the button 42 when the tab 30 is hooked over the button 40 in order to securely hold the flap folded upon itself.
- 40 Breast pockets 43 and 44 as well as a pencil pocket 45 are secured to the front of the garment in that portion thereof covering the wearer's chest.
- Referring to Figures 2 and 3 it will be seen that 45 an arcuate pad 46 is disposed on the inside of the back of the garment below the neck opening 16 and extends to the top of the shoulders. This

pad relieves pressure upon the neck of the wearer so that the garment may be comfortably worn under all conditions of service, such as for instance over oil or water repellent clothing.

From the above description it is thought that 5 the construction and operation of my invention will be fully understood without further explanation.

What is claimed is:

1. A sleeveless garment of hip length opening at 10 the front, a vertical line of fasteners for the open front of the garment extending from the hip to the neck of the garment, a flap extending transversely across in front of the abdominal part of the garment above the lower edge of the garment, pockets in the flap, said flap being fixedly secured at one end to the garment at one side of said line of fasteners, means removably securing the opposite end of the flap to the garment on the other side of said line of fasteners, said 15 flap when so secured covering the lowermost fasteners, said flap being adapted to be folded back upon itself toward the secured end thereof to permit access to the lowermost fasteners of the line of fasteners, and means for fastening the flap 20 in folded position on the garment.

2. A sleeveless garment of hip length opening at the front, a vertical line of fasteners for the open front of the garment extending from the hip to the neck of the garment, a flap extending 30 transversely across the front of the abdominal part of the garment above the lower edge of the garment, pockets in the flap, said flap being fixedly secured at one end to the garment at one side of said line of fasteners, means removably securing the opposite end of the flap to the garment on the other side of said line of fasteners, said 35 flap when so secured covering the lowermost fasteners, said flap being adapted to be folded back upon itself toward the secured end thereof to 40 permit access to the lowermost fasteners of the line of fasteners, tabs on the secured end of the flap, and fastening devices on the tabs adapted to engage the free end of the folded flap and hold the folded flap laterally of said line of fasteners. 45

VICTOR THOMAS POWELL.
